LOCK STRUCTURE

Filed Jan. 10, 1930

UNITED STATES PATENT OFFICE

GORDON L. ROSS, OF KANSAS CITY, MISSOURI

LOCK STRUCTURE

Application filed January 10, 1930. Serial No. 419,836.

This invention relates to lock structures and has for its primary object the provision of new, novel and cheaply constructed mechanism and parts for locks of various types and 5 styles that will preclude moving the primary bolt of the same to the unlocked position by unauthorized persons or those other than the ones holding the key for the particular lock within which has been placed devices made 10 in accordance with the broad concepts of the present invention.

One of the main objects of this invention is to provide means within a lock for serving a double purpose in connection with the primary bolt thereof: first, the locking of the 15 primary bolt in the well-known locked position, and second, the further use of a secondary bolt or plunger which positions itself in an effective way to act as a secondary lock 20 for the primary bolt.

Another object of this invention is the provision of a secondary or auxiliary lock for the primary bolt of any ordinary or specially 25 constructed lock, which moves to its operative position as the primary bolt is being disposed to the locked position.

A still further object of this invention is to provide a novel lock structure which has a positively acting secondary lock for the primary bolt thereof, movable in a self-actuating manner to the effective position when the lock is carried to the locking position by the element to be secured against movement by said lock.

An even further object of the present invention is the provision of a means within a lock which acts upon the primary bolt thereof to hold the same in the locked position until the manually controlled actuating means is 30 used to move both the primary bolt and its locking means to the unlocked position.

Other objects of this invention will appear during the course of the detailed specifications, wherein but the preferred form of the 45 invention has been shown embodied in a lock having the conventional type of parts. The parts made in accordance with this invention may be modified as to form and specific structure, and the materials used to make up 50 the novel parts of this lock may be stamped,

cast, pressed, or otherwise formed in a manner to render the lock structure cheap to make and effective in operation, as well as easy to assemble.

It is understood that many forms of "picking" is practiced when unauthorized persons move locks of the commercial type to the unlocked position without the use of a proper key. One of the most common, is the introduction of an instrument of some sort to the primary bolt to move it to the unlocked position against the normal holding action of the standard parts now used. As a result of this understanding, it is the object of this invention to supply broad novel means for precluding such action. Objects of a more important nature such as the combination of parts in an effective manner will also appear during the specification.

With reference at this point to the form of the invention illustrated in the accompanying drawings,

Figure 1 is a vertical central cross section of a lock made in accordance with this invention showing the primary bolt and its locking plunger in the locked position.

Fig. 2 is a horizontal cross section through the lock, taken on line II—II of Fig. 1, and

Fig. 3 is a fragmentary side elevation of the primary bolt and plunger assembly, parts broken away for clearness.

Like reference characters refer to similar parts of the lock throughout the several views of the drawings, and the numerals 4 and 6 indicate a door and door casing respectively, and 8 indicates the ordinary modern type of molding against which the door 4 stops when the same is in a position to be locked. The lock structure here shown is of the mortise type, but it is understood that any style might be constructed to embody the advantages, details and structure of the present invention. The casing 10 houses the working parts of the lock, and the same may consist of a primary bolt 12 which is actuated by a spring or the like 14 to the projected or locked position as shown in Fig. 1. The forward or locking end of primary bolt 12 has a passage 16 formed therein which communicates with an opening 18 and slot 20. Primary

bolt 12 is supported for sliding movement by the ears 22 formed as a part of casing 10 as well as by the opening through the front of casing 10. Opening 24 should register with 5 a similar hole 26 formed through strike plate 28 secured to door casing 6, and when the primary bolt of the lock is disposed in the locked position, it should pass through both opening 24 and hole 26.

10 A plunger 30 should be slidably mounted for reciprocating movement in opening 16 through the use of a pin 32 and slots 34 formed in the side of primary bolt 12. As shown in Fig. 2, the pin 32 extends beyond 15 the sides of bolt 12 to be engaged by a spring 36 which constantly urges plunger 30 toward the outer end of primary bolt 12. Forming a part of plunger assembly is the rearwardly and upwardly extending arm 38 which has 20 a locking portion 40 formed thereon as illustrated in Figs. 1 and 3. This locking portion 40 should consist of a plurality of lugs formed as shown which are moved between the end member 42 of primary bolt 12 and the 25 lock lug 44 rigid to case 10. This action is assisted by spring 56 carried by bolt 12. Gravity will also assist in this action.

In the position shown in the drawings, 30 Figs. 1 and 2, the lock assembly is in the locked position with the primary bolt secured against movement by the locking portion 40 of the plunger arm 38 which, as previously described, is pivotally connected to plunger 30 through the pin 32.

35 As the door 4 is being closed, bolt 12 engages strike plate 28 which has a member 46 formed integrally therewith in the form of a lug which is adapted to pass into the bolt 12 through the slot 20 as the bolt is being disposed to the locked position through the action of spring 14. When this member 46 engages the end of plunger 30, it causes it to move back into the passage 16 against the action of spring 36, and as soon as the locking portion 40 has reached the position between the end of bolt 12 and the lock lug 44, the lugs formed on this portion 40 will drop to the position shown to lock the primary bolt 12 against movement. This action also locks 45 the plunger against movement until the manually actuated member mounted on the shaft 48 is turned to lift arm 38 through the cams 50. These cams 50 will hold arm 38 up out of engagement with the end of bolt 12 and away 50 from the lock lug 44 and the projection 52 will travel to strike the upturned portion of bolt 12 to pull the same out of engagement with the hole 26 formed in strike plate 28. Thus, the manually operable means located 60 on shaft 48 and on the side of the door which swings inwardly moves all the assembly to the unlocked position. Likewise, a properly formed key might be introduced through the hole 54 to perform the same function.

65 When the locking portion 40 is raised, the

spring 36 will assist the movement of plunger 30 back to the starting point as bolt 12 is moved to the unlocked position.

It is to be understood that any means for moving the plunger 30 to the locked position might be employed, the form here shown is merely one embodiment of the invention.

70 In supplying the springs for the lock mechanism, they should be of strengths suitable to act as previously described. For instance, the 75 spring 14 tending to force the bolt 12 to the locked position is the strongest, and should be bifurcated as shown to clear the extended portion of the plunger arm 38 when it is operated. Spring 36 is next in order of 80 strength, and it should be formed to present a pair of coils one positioned on each side of the bolt 12 as illustrated in Fig. 2. The smaller leaf spring 56 is the weakest of the 85 series of springs, and tends to assist gravity in forcing locking portion 40 into place when the member 46 has moved plunger 30 along the passage 16 formed in bolt 12. This spring 56 yields when the key or manually-operated member mounted on shaft 48 is turned to lift locking portion 40 out of the locked position.

90 As shown in Fig. 2, strike plate 28 may be arched slightly to assist the bolt 12 in its movement as the door 4 is being closed.

95 Having thus described the invention, to the details of which it is desired not to be limited, except as defined by the spirit of the broad invention and the scope of the appended claims, what is claimed and desired to be secured by Letters Patent is:

100 1. In a lock, a hollow primary bolt, a plunger, a lock lug and a device for moving said plunger against said lug as the primary bolt is being disposed to the locked position whereby both the primary bolt and plunger are locked against relative movement said plunger being carried centrally within the bolt, an opening in the end of the bolt, a slot in the side thereof, said opening and slot being connected to allow entrance of the said device into the bolt to move the said plunger as said primary bolt moves to the locked position.

105 2. In a lock structure, a hollow primary bolt, a plunger associated therewith for relative movement, a lock lug, a locking portion formed by the plunger, a strike plate having a hole therethrough and operating apparatus carried by the plate and partially restricting said hole engageable with said plunger to move its locking portion against said lock lug as the primary bolt is being disposed to the locked position.

110 3. In a lock, a primary bolt, a plunger movable therewith and means, remote from the lock for engaging said plunger, as the primary bolt is being disposed to the locked position, to move the plunger to the locked position, said means including a strike plate.

member intersecting the path of travel of said plunger when the primary bolt is in the locked position.

4. In a lock, a primary bolt, a plunger, a central longitudinal passage formed within said primary bolt, said plunger being mounted for reciprocating movement in said passage and a member engageable with the plunger to actuate the same as the primary bolt is being disposed to the locked position, said member intersecting the path of travel of said primary bolt.

5. In a lock, a primary bolt, a plunger, a central longitudinal passage formed within said bolt, said plunger mounted for movement within said passage and a plunger engaging member projecting within said passage to move said plunger as the primary bolt is being disposed to the locked position.

20 6. In a lock, a primary bolt, a plunger, a lock lug, a plurality of locking shoulders integral with said plunger, said shoulders movable with said plunger to a position against said primary bolt and lock lug as the primary bolt is being disposed to the locked position, whereby both are locked against relative or unitary movement, said plunger housed centrally within the primary bolt with a portion thereof projecting therebelow, the shoulders being formed by said projecting portion.

35 7. In a lock structure, a primary bolt, a plunger slidably housed therein, a lock lug, a locking portion formed by said plunger, and means for moving the plunger against the lock lug as said primary bolt is being disposed to locking position to lock said primary bolt against movement, said means including a stationary strike plate member projecting into said primary bolt and engaging the said plunger therein when the structure is in the locking position.

40 In testimony whereof I hereunto affix my signature.

45 GORDON L. ROSS.
